UNITED STATES PATENT OFFICE.

ROBERT W. KELLEY, OF WELLINGTON, TEXAS.

VALVE FOR TOILET-BASINS.

1,050,661.

Specification of Letters Patent. Patented Jan. 14, 1913.

Application filed August 28, 1912. Serial No. 717,586.

To all whom it may concern:

Be it known that I, ROBERT W. KELLEY, a citizen of the United States, residing at Wellington, in the county of Collingsworth and State of Texas, have invented new and useful Improvements in Valves for Toilet-Basins, of which the following is a specification.

This invention relates to valves for toilet basins or the like and has for an object to provide controlling means for the valve which may be actuated manually exteriorly of the bowl so as to obviate the necessity on part of the operator of his placing his hand in the water when it is desired to discharge the contents of the bowl.

Another object of the invention is to provide valve controlling means which will be positive in action, one which will operate to invite a gravitational seating of the valve so as to eliminate the use of springs or the like, and one which will include companion elements that may be readily connected with or disconnected from each other as the occasion may demand.

In the drawing forming a portion of this application, and in which like letters of reference indicate similar parts in the several views:—Figure 1 is a section through a 30 toilet basin showing the application of the valve controlling means thereto. Fig. 2 is a perspective view of a portion of the valve rod. Fig. 3 is a perspective view of a portion of the rocking lever.

The bowl 1 conventionally shown herein may be of any well known construction, being preferably provided at its bottom with an interiorly threaded discharge opening 2 in which is secured the upper extremity of 40 a waste pipe 3, while the lower end of the pipe is connected through a substantially T-coupling 4 with a lower branch 5 of the waste pipe. A tube or pipe section 6 has detachable connection at 7 with the ledge 8 of the bowl. The lower end of the tube 6 is disposed above the plane of the coupling 4 and is connected thereto by a downwardly extending tube 9. A valve rod 10 is movable vertically in the waste pipe 3, being 50 provided at its upper end with a plug valve 11 which is adapted to be extended into the upper end of the waste pipe whereby to effect a proper seal of the basin 1 to prevent the discharge of the water therefrom. The 55 lower end of the valve rod is bifurcated at 12, providing spaced portions 13 which have

formed therein oppositely disposed substantially bayonet slots 14. An angularly disposed rocking lever 15 is pivotally mounted in the tube 9, and as shown said lever is 60 provided with a long branch 16 which extends in the direction of the coupling 4 and which is terminally curved upwardly as at 17 and fitted between the portions 13 of the valve rod whereby the lateral retaining 65 studs 18 will be disposed in the vertical legs 19 of the slots 14. At the opposite end the lever 15 is provided with a short arm 20 which extends into the elbow 21 at the lower end of the tube 6 and which is pivotally connected 70 with the lower end of a vertical actuating rod 22. The rod 22 is slidable in suitable guides 23 in said tube 6 and as illustrated the upper end of the rod extends above the plane of the ledge 8 where it is 75 connected with a manipulating lever 24. The lever 24 is pivotally connected with the upper end of a post 25 which extends through the ledge 8 and which is supported from a suitable bracket 26. The bracket 26 80 is provided with the embracing portions 27 receiving the pipe 3 and the tube 6 as shown in Fig. 1 of the drawing.

Now that the details of construction of the device are disclosed it is seen that the 85 major portion of the rocking lever 15 is disposed below the plane of the pivot of the lever, so as to contribute its weight to the weight of the valve rod 10 to insure a gravitational closing of the valve 11. Adjustment 90 of the lever 24 in one direction imparts rocking movement to the lever 15 whereby the valve 11 will be adjusted to an opened position to permit the water to be discharged from the bowl. The connection between the valve rod 10 and the portion 17 of the rocking lever is such that the rod 10 can be adjusted to a position to cause the valve 11 thereof to be disposed at a considerable distance above the plane of the bottom 100 of the basin 1 where it may be grasped by the hand and manipulated so as to cause a disconnection of the studs 18 from the portions 13 of the valve rod as is evident. In this manner it is seen that the valve rod can 105 be entirely withdrawn from the waste pipe to facilitate repairing or grinding of the plug 11.

I claim:—

A bowl having a waste pipe extending 110 therefrom, a tube extending upwardly at an angle from and communicating with

said waste pipe, a second tube extending through the ledge of the bowl and connected with the upper end of the first tube, a valve rod slideable vertically in the waste pipe, a 5 valve carried by said rod and adapted to close against one end of the waste pipe, a rocking lever mounted in the tube and having an attaching long arm terminally disposed in axial alinement with the waste pipe 10 and detachably connected with the valve rod, said rocking lever having a short arm terminally disposed in axial alinement with the second tube, an actuating rod operatively

connected with the short arm; and a controlling lever connected with the actuating 15 rod, the point of attachment of the long arm of the rocking lever with the valve rod being disposed below the plane of the pivot of the rocking lever whereby the valve is gravitationally held in a closed position.

In testimony whereof I affix my signature in presence of two witnesses.

ROBERT W. KELLEY.
